PROCESS FOR PRESERVING MATERIALS OF
THE POWDERY OR MEALY TYPE

Egon Herbert Schwarz, Zurich, Switzerland

No Drawing. Application September 25, 1940, Serial No. 358,767. In Switzerland October 5, 1939

1 Claim. (Cl. 99—150)

It is a generally known fact, that all natural materials, or artificial raw materials, also those rendered into powder form, or their mixtures, absorb, respectively take up moisture in each case from their immediate surroundings, owing to their hygroscopic properties. These materials or mixtures, therefore, are subject to variations after a short while, as regards their physical condition, chemical composition or their biological properties, making them useless for the purpose, for which they had originally been intended. Materials kept or stored in powder form, lose their original properties, and thereby, as a rule, the greatest part of their possibilities for use, due to different internal or external harmful influences, such as mouldiness, mustiness, dustiness, moth or worm attack, infection, etc.

Until now, different processes have been proposed and employed, for avoiding these harmful influences which very often cause complete destruction of the goods; for instance, the storage of the materials in air-tight and closed receptacles, the addition of chemical substances or their constituents, the pressing into compact form, etc. The well-known pressing process has provided the most successful, as a protection towards external harmful influences. However, by means of the well-known stamping in and pressing process, whereby materials or mixtures in powder form should keep for a considerable time without altering their original physical, chemical and biological properties, i. e., in a manner corresponding to the original intention of these materials, the desired result could not be obtained, and this for at least one reason, namely, that the materials to be preserved, were not subjected to the appropriate pretreatment, for example, sterilization, for destroying any possible bacillus, microbes, spores, etc.

Such materials which were pressed or stamped in without any pretreatment, showed within the shortest time very serious changes, with regard to their physical properties, and their chemical composition, owing to the presence of micro-organisms, causing decomposition or other alterations. The desired result therefore, i. e., the preserving of these materials towards internal and external influences for a longer period, could not be completely obtained.

The purpose of the present invention, is to subject natural or artificial materials in powder form, destined for long storage, resp. for preservation, to such pretreatment before mechanical pressing is resorted to, and without the addition of any foreign matter, for example chemicals or

preserving medium; thereafter to press these materials under such conditions, that after pressing, they retain their original chemical, biological and physical properties, without any change in quality whatsoever and with the advantage, that they can be kept for an unlimited time, and can be used at any desired period, and furthermore, presenting solidity, and volume reduction, facilitating storage in a mechanical sense.

The invention calls for a series of preparatory work, and a special method of pressing:

(1) The sterilization of the materials, i. e., destruction of microorganisms (bacilli, microbes, spores, eggs, larvae, etc.), contained in the materials by nature, or entering afterwards, by means of violet rays, and the like.

(2) The suppression of the elastic properties of the materials, by means of heat influences.

(3) The elimination of dust from the materials, by means of cooling and prepressing.

As mentioned above, the known method for preventing materials in powder form, and their mixtures, from becoming spoilt, or from changing their chemical composition, consists in stamping or pressing. The press processes known, however, possessed several fundamental disadvantages. One of the disadvantages of the known processes consisted therein, that the materials to be pressed still contained microbes, bacilli and spores which were not eliminated, but chemicals were added to the materials, resp. these materials were subjected to water steam, and such like, to prevent spoiling from taking place. Another disadvantage of the known processes was to be found in the fact, that the most important matter was overlooked, namely, that the materials in powder form, of different composition, could only be subjected to very definite pressures of the press, in accordance with their physical and chemical properties.

Another point which was overlooked, was, that most materials in powder form presented great elasticity, resulting in, comparatively speaking, great reaction powers which occurred during pressing. Finally, a factor of the most deciding importance, has not been taken into account, i. e., that materials in powder form, cannot be pressed with the usual piston, fitting closely to the pressing mould and rubbing along the walls of same, because on account of the proportionately high mechanical pressure, the tightly fitting piston, causes a proportionately great quantity of heat through friction, and since the quantity of air still contained in the material to be pressed cannot escape, this

quantity of air becomes heated, creating car-

bonized appearances in the powdery material, thereby subjecting the physical, chemical and biological properties of the pressed goods to an alteration. As a result of this, the pressed material could not be used for its original purpose. The exposure of the materials to the influence of water or water steam, had the harmful effect, that the water or steam remaining in the material created moulding tendencies. The addition of chemicals was accompanied by the disadvantage, that the pressed materials had to be purified, according to different processes, before being put to use, so as to eliminate any matter eventually contained therein which might harm the human or animal organisms. Until now shaped pieces coming from the press moulds become split immediately, or after a few hours; in fact, they fell to pieces, and were subjected to detrimental changes in their composition. These disadvantages were to be found in the incorrect construction of the press instruments and moulds, and in incorrect pressures used during pressing. All these disadvantages can be avoided with the present invention. As will have been noted from the instructions given for pretreatment, no foreign matter, for example, preserving or agglutinant means are added to the material to be preserved, resp. pressed.

After the pretreatment mentioned has been carried out, the materials are ready for pressing, and the process, according to the invention, consists therein, that a piston press, or such like is used for briquetting, i. e., shaping into bricks, whereby the piston diameter in comparison to the stroke, and to the diameter of the cylinder, or other cross-section bodies of the pressing chamber, are in a certain relation to each other, and furthermore, air-slits are to be provided in the piston, according to the materials to be pressed, permitting any air, gases, etc., becoming liberated from the material by pressing, to escape, in this manner a complete briquetting is the result.

The following dimensions have proved especially suitable:

Supposing, that the interior diameter of a pressing mould is d cm., the height of the inner pressing chamber of the pressing mould ought to be h cm., therefore,

$$h = 2.4 \times d \text{ (measured in centimeters)}$$

The dimensions of the piston are as follows:

The diameter of the piston (d_1) must be 0.4 mm. smaller than the interior diameter of the pressing chamber (d), in the event of the latter having at the most 20 cm. In this case the following equation would come into question:

$$d_1 = d - 0.04 \text{ (measured in centimeters)}$$

If d measures at the most 50 cm., d_1 must be 0.5 mm. smaller than d , and if d has at the most 75 cm. d_1 must be 0.6 mm. smaller than d .

The dimensions of the air channels provided on both sides of the pistons are as follows:

If d is 25 cm. at the most, the cross-section of these channels is to amount to 2×1 mm.

If d is 50 cm. at the most, the cross-section of these channels is 3×1.5 mm.

The diameter of the piston must therefore be smaller according to the above mentioned dimension, than the width of the pressing mould, so that any friction along the walls of the pressing mould is avoided in this manner, and any heat from friction which until now caused cases of carbonization in the pressed material does not arise.

The pressed goods retain therefore their original colour, composition and biological properties.

For the purpose of avoiding any material becoming attached to the piston, the lower surface of the piston can be carried out in a concave manner. The dimensions of this concave construction are:

0 mm. at the rim of the piston, 2 mm. at the vertical centre line of the piston, providing that the diameter of the piston is 25 cm. and 3 mm. at the most, and providing that the piston diameter amounts to 50 cm. at the most.

After the material has been emptied into the pressing mould, a thin piece of paper or such like can be placed by hand, or by means of an appropriate device on the material before the pressing piston is put into action, this, in order to avoid any material becoming attached to the piston. The thin piece of paper can easily be removed afterwards from the completed shaped piece.

The amount of mechanical pressure to be used, depends upon the dimensions of the pressing mould, i. e., upon the diameter and height of same, upon the properties of the material to be pressed, and upon the height of the material filled into the pressing cylinder for pressing. The pressures to be used for the different cases, relating to different important foods, are given in kg./cm.^2 as follows:

(a) For such kinds of meals as bran, cement flour, and generally, all dry powdery materials, with no oil or grease contents, the amount of mechanical pressure to be used is (p):

$$\begin{aligned} p &= 3 \times d \text{ if } sh = 1 \times d \\ p &= 4 \times d \text{ if } sh = 1.5 \times d \\ p &= 5 \times d \text{ if } sh = 2 \times d \end{aligned}$$

(b) For smooth kinds of meals, such as rye, barley, indian corn, and generally, where all powdery and mealy materials, containing very little oil or grease, are concerned, the amount of mechanical pressure to be used, is (p):

$$\begin{aligned} p &= 2 \times d \text{ if } sh = 1 \times d \\ p &= 3 \times d \text{ if } sh = 1.5 \times d \\ p &= 4 \times d \text{ if } sh = 2 \times d \end{aligned}$$

(c) For mixtures of mealy kinds of materials with butter oil, or grease, for artificial manure, milk powder preparations, and generally, for all mixtures containing a larger quantity of grease, the following mechanical pressure (p) is to be used:

$$\begin{aligned} p &= d/10 \text{ if } sh = 1 \times d \\ p &= d/6.66 \text{ if } sh = 1.5 \times d \\ p &= d/5 \text{ if } sh = 2 \times d \end{aligned}$$

Whereby the meaning of:

p =the mechanical pressure to be used, in kg./cm.^2

d =the diameter of the pressing chamber, in cm.,

and

sh =the height of the pressing cylinder for pressing the material filled in, in cm.

If any material treated in powder form according to the methods of the invention for the preparatory stage, is afterwards pressed in the appropriate press moulds in accordance with the above formulas, a shaped piece will be the result which has kept in every way its original properties, with the advantage, that it can be kept any length of time, and no exterior influences (smells, heat, cold, gases, etc.) can affect it. No harmful microorganisms (bacilli, eggs, spores, etc.) will have a chance to develop in such a product.

The material is fire-resisting, its outer surface—in the event of the shaped piece being stored without any exterior protective wrapping—will only be very slightly affected by water or any other liquids. Tests made showed a penetration of 0.5 to 1 mm. depth.

An exceptionally important advantage of the invention consists therein, that the pressed material loses 25–55% of its volume, due to pressing and interior air expulsion, depending upon the chemical composition and physical condition of said material, and regarded from the point of view of storage, delivery and treatment, this means a great progress. Finally, the pressed shapes, can be stored anywhere desired, without any further treatment or airing, even underground sites would have no effect on same, which turns out to be a great economy, in comparison to storage and treatment of unpressed goods.

The best method for protecting the shaped piece from becoming dusty, dirty or being affected by other influences, consists in wrapping same into Cellophane paper, by sticking down the edges. On the other hand, a special dipping lacquer, on the basis of acetylcellulose can be used to great advantage.

The finished shapes (preserves) can then be

used by taking off the wrapping, and the product crushed by hand, or by some mechanical device. Thereafter the crushed material is absolutely equal to the fresh product.

5 To conclude, it is to be pointed out, that transgression of the present instructions as regards dimensions of the pressing mold, and of the piston, either in the negative or the positive sense, or the increase or decrease of the mechanical pressure mentioned, would cause a disadvantageous change in the physical and biological properties of the powdery material, making any preserving out of the question and its original purpose would not have been served at all.

10 13 I claim:

Method of preserving materials of the powdery or mealy type which comprises the steps of sterilizing the materials, suddenly lowering the temperature of the materials, applying a preliminary pressure to said materials and forming a preliminary body, thereafter subjecting the preliminary body to final pressure to produce the final shaped product, allowing air to escape from within said preliminary body during the final pressing action, fresh air being also admitted to the outside of said preliminary body to cool it during the final pressing action.

EGON HERBERT SCHWARZ.
